BLIND STITCH SEWING MACHINE

Ralph Simpson Kelso, St. Louis, Mo., assignor to
 Lewis Invisible Stitch Machine Company, St.
 Louis, Mo., a corporation of Maine

Application January 4, 1936, Serial No. 57,613

22 Claims. (Cl. 112—176)

This invention relates to new and useful improvements in blind stitch sewing machines generally, although more particularly to blind stitch sewing machines employed in hemming operations.

The principal object of the invention is to provide a blind stitch sewing machine of the double thread chain stitch type for seaming hems, by means of which a line of stitches will be formed to unite the hem fold to the body fabric, the connecting portions of the needle thread between adjacent needle loops being positioned in a straight line in parallelism with the inner edge of the hem and the enchain looper thread loops being disposed under the inner edge of the hem and thereby concealed from view.

Another important object of my invention lies in the provision of a threaded non-avoiding reciprocating looper which cooperates with a needle mounted for reciprocation across the line of feed, the looper having a path of travel in a single straight line in the line of feed and being located entirely on that side of the ridge forming element opposite the point of needle penetration in the fabric, whereby the feed of the fabric and the rearward stroke of the needle will effect the opening of the looper thread loop for entrance by the needle.

A further object of the invention lies in the provision of means for reciprocating the looper whereby the speed travel of the looper during the last part of its forward stroke will be increased to thereby better insure the looper entering the needle thread loop, and to decrease the speed travel of the looper during the first part of its backward stroke to thereby better insure the needle entering the looper thread triangle.

With these and other objects in view which will more fully appear, the nature of the invention will be more clearly understood by following the description, the appended claims, and the several views illustrated in the accompanying drawings.

In the drawings:

Figure 1 is a top plan view of a sewing machine constructed in accordance with my invention,

Figure 2 is a left hand elevation thereof, the base being omitted,

Figure 3 is a perspective view of the looper supporting bracket,

Figure 4 is a perspective view of the looper guide,

Figure 5 is a partial rear end elevation, partly in section, showing the driving connections be-

tween the main shaft and the 4-motion top feed, and between the main shaft and the looper,

Figure 6 is a diagram showing the variable looper speed travel,

Figure 7 is a detail view showing the driving connection between the main shaft and the oscillatory ridge carrying shaft,

Figure 8 is a detail elevation showing the reduction gear coupling between the main shaft and the pitman which oscillates the looper carrying shaft,

Figure 8a is an elevation of the driving disc,

Figure 9 is a detail elevation of the top feed mechanism, the view showing particularly the means for imparting up and down movements to the feed dog,

Figure 10 is a detail view showing the mechanism for imparting the back and forth movements to the feed dog,

Figure 11 is a bottom plan view of the forwardly extending arm showing particularly the presser foot, the looper mechanism, and the top feed mechanism,

Figure 12 is a top plan view of the presser foot,

Figure 13 is an enlarged view showing a hem seamed by my invention,

Figure 14 is an enlarged view of the presser foot, the needle, and the fabric being hemmed, the view showing the looper at the rear end of its stroke and the needle at the forward end of its stroke,

Figure 15 is a similar view but showing the looper moving forwardly through the needle thread loop,

Figure 16 is a similar view but showing the looper at the forward end of its stroke and the needle at the end of its backward stroke, and

Figure 17 is a similar view but showing the looper being moved rearwardly and the needle in a position about to enter the looper thread loop.

Like reference numerals designate corresponding parts throughout the several figures of the drawings.

My invention is adapted especially for joining a hem A to a body fabric or base layer B by a line of blind stitches, as shown in Figure 13. The inner edge of the hem is indicated at a, and the hem may have an inturned edge portion a' if desired. A needle thread C and a looper thread D are employed to form a line of Grover and Baker stitches, which are otherwise known as "double-lock" and "double-chain" stitches. The stitches include needle thread loops c which are spaced equidistantly apart and pass downwardly

through the hem at points c' , the connecting portions of the thread between the loops being arranged in a straight line and in parallelism to the inner edge a of the hem. Certain of these 5 needle loops enter and emerge from the upper face of the body fabric as indicated at c^2 to thereby form "anchor" stitches E which function to join the hem with the body fabric, while other needle loops miss the body fabric entirely to thereby form resultant "skip" stitches F . The 10 enchain loops d of the looper thread which are concatenated with the needle loops c , are all located between the hem and the body fabric and are consequently concealed from view by the 15 hem. It will be understood, however, that all "anchor" stitches, or alternate "anchor" and "skip" stitches, or any combination thereof, may be employed.

The machine of my invention includes a base 5 having a standard 6 projecting upwardly from the rear right hand corner thereof, an arm 7 which extends laterally from the upper end of said standard, and an arm 8 which extends forwardly from the left hand end of the arm 7. 20 Fixed to the free end of the arm 8 in the usual manner is a horizontal presser foot 9 having a centrally located and longitudinally extending opening 10 formed therein. Journaled in the laterally extending arm 7 is a main shaft 11 and 25 journaled in the arm 8 is an oscillatory needle shaft 12 which is driven from the main shaft by a connection indicated generally at 13. The needle shaft 12 is disposed directly above the opening 10 in the foot, and fixed to the outer end of 30 the shaft is a needle arm 14 carrying a curved needle 15. Thus when the needle shaft 12 is oscillated the needle 15 will reciprocate transversely across the opening 10 in the presser foot. It will be noted at this time that the penetrating 35 stroke of the needle 15, as viewed from the front of the machine, is from right to left.

Rigid with the base 5 is a post 16 which is located in a plane in advance of the standard 6 and pivotally supported on the upper end of 40 this post is a work support 17 having a lateral extension 18 which projects under the presser foot 9, the work support 17 being yieldably held against depression by a spring (not shown). The upward movement of the work support is adjustably limited by a stop 19 mounted on the work support 17 and cooperating with the machine frame as shown in the Mueller Patent 2,018,186, Oct. 22, 1935.

As previously stated this machine is particularly intended for hemming operations and to 45 this end means are provided for projecting a ridge of material upwardly through the presser foot opening 10 into needle penetrating position during each cycle. A disc 20 is fixed to the end 50 of a rock shaft 21 which is journaled in bearings on the under side of the work support 17. The disc is provided with high and low peripheral portions 22 and 23 respectively, arranged in tandem, and this shaft 21 is oscillated for different 55 angular amounts by driving connections with the main shaft 11 whereby the high and low portions of the disc will register successively with the needle during the penetrating strokes thereof. Thus at the rear end of one oscillation stroke 60 the needle will engage both the hem A and the body fabric B to form a resultant "anchor" stitch E and at the rear end of the next stroke the needle will engage the hem A only to form a resultant "skip" stitch F. The driving connections 65 between the main shaft 11 and the disc shaft 21

are shown in Figures 7 and 8 and are as follows: Fixed to the main shaft 11 is a driving eccentric 24 and surrounding this eccentric is an eccentric sleeve 25 which is positively rotated on the eccentric but at one-half the speed thereof. A disc 26 is loosely mounted on the main shaft 11 and is provided with a radial slot 27 for receiving a slide block 28 fixed to the eccentric sleeve 25 by a shank 29. A driving gear 34 is fixed to the main shaft 11, and rotatable on a 10 stationary shaft 32 mounted in the frame standard 6 is a reduction gear unit including a large gear 33 and a small gear 35, the former being in constant mesh with the driving gear 34 and the latter being in constant mesh with a gear 31 fixed to the disc 26. This reduction gear coupling is similar to that shown in the Mueller Patent 1,989,602, of Jan. 29, 1935. The gear coupling ratio is such that the eccentric sleeve 25 is rotated once during every two revolutions of 15 the main shaft 11. In order to rock the disc shaft 21 from the eccentric 24 and eccentric sleeve 25, I have provided a link 36 having one end fitting around the eccentric sleeve 25 and the other end 20 pivotally connected to a rock arm 37 which is clamped to the disc shaft 21. Thus by these connections the high and low portions 22, 23 of the disc will successively register with the needle. A vertically yieldable work clamp 38 is mounted on the lateral extension 18 of the work support 30 25 and cooperates with the lower face of the presser foot 9 in the usual manner to clamp the fabric against the thrust of the needle.

A top feeding mechanism for feeding the material rearwardly up to and past the needle includes a 4-motion feed dog 39 having a front feed section 40 and a rearwardly spaced feed section 41, said sections being connected by a longitudinally extending bridge 42 forming a resultant opening 43 thereunder. This feed dog 39 is attached to a feed bar 44 by screws 45. The feed sections operate in the opening 10 of the presser foot and against the upwardly spring pressed work clamp 38, the front section 40 being located in front of the needle path and the rear section 41 in rear of said path. The feed bar 44 is raised and lowered by a train of mechanism from the main shaft 11, and is moved back and forth by a train of mechanism operated from said main shaft. A bell crank lever 46 is pivoted at its angle as at 47 to the forwardly extending arm 8 of the frame. This bell crank lever includes a forwardly extending arm 48 and a downwardly extending arm 49. A link 50 is pivotally connected at its upper end as at 51 to the arm 48 and at its lower end as at 52 to the feed bar 44. The rear end of the feed bar is provided with an inclined open ended slot 53 which has sliding connection on a bearing pin 54 fixed to the forwardly extending frame arm 8. A pitman 55 is 55 pivotally connected at its forward end as at 56 to the depending arm 49 of the bell crank lever 46 and the rear end of this pitman is connected with an eccentric 57 fixed on the main shaft 11. It will thus be seen that upon rotation of the 60 main shaft, the eccentric 57 will rock the bell crank lever 46 which, through the medium of the link 51, will raise and lower the feed bar 44. In order to move the feed bar back and forth, I have provided a slotted segment 58 which is 65 pivoted at its upper end as at 59 to the forwardly extending frame arm 8. A driving link 60 is pivotally connected at its forward end as at 61 to the feed bar 44 and the rear end of this link is adjustably connected to the slotted segment 70 75 75

58 by a clamping bolt 62, the slot of the segment being arcuate and having for its center the pivot 61. The slotted segment 58 is pivotally connected as at 63 to a sleeve 64 which surrounds an eccentric 65 fixed on the main shaft 11. Thus upon rotation of the main shaft 11, the eccentric 65 will impart swinging movements to the slotted segment 58 and this segment through the medium of the link 60 will impart back and forth movements to the feed bar 44. By adjusting the clamping bolt 62 lengthwise of the slotted segment 58 the length of feed travel imparted to the feed dog 39 may be readily varied.

Cooperating with the needle is a looper 66 which is threaded with the looper thread D. This looper is fixed to the forward end of a looper bar 67 extending longitudinally of the frame arm 8 and alongside of the feeding mechanism. This looper bar is slidably mounted for longitudinal movements in spaced bearings 68, 69 mounted on a bracket 70 which is attached by screws 71 to the frame arm 8. The looper 66 has a non-avoiding movement with respect to the needle 15 and reciprocates in the line of feed and along a single straight horizontal line which passes above the needle. This looper is disposed on that side of the disc 20 opposite the point of needle penetration. The looper therefore travels not only above the needle 15 but also above the presser foot 9 and its path of movement is in the line of feed or at right angles to the plane of needle reciprocations. In order to reciprocate the looper longitudinally from the main shaft 11, I have provided the looper bar 67 with a depending clamping arm 72, the upper end of the arm being formed into a split clamp 73 which surrounds the looper bar 67 and is clamped thereto by a screw 74. A pitman 75 has its forward end pivotally connected as at 76 to the lower end of the clamping arm 72 and its rear end engaged with an eccentric pin 77 fixed to a sleeve 78 secured on the main shaft 11. The looper bar 67 is retained against axial rotation by means of a guide shoe 79 which is preferably formed integral with the clamping arm 72 and cooperates with an upwardly extending guide plate 80 attached to the bracket 70 by screws 81. It will be noted that the looper bar 67 is in the same horizontal plane as the main shaft 11 and that the pivotal connection 76 is located below said plane. Consequently a variable speed travel is imparted to the looper during its backward and forward movements whereby the looper during the first part of its forward stroke will have a relatively fast speed travel while entering the needle thread loop, and whereby the looper will have a relatively slow speed travel during the first part of the backward stroke thereof while the needle is entering the looper thread loop. In Figure 6, I have disclosed a diagram showing the variable looper travel.

The needle 15 is provided along its forward side with a shallow groove or spreader 82 which functions to drag the looper thread loop which is around the needle, toward the right and out of the path of the looper whereby the looper will with certainty enter the needle thread loop without engaging said looper thread loop.

The needle 15 has its path of movement across the line of feed and under the bridge 42 of the feed dog. Consequently the front feed portion 40 functions to feed the material up to the needle and the rear portion 41 of the feed dog functions to feed the material rearwardly away from the needle.

An edge guide 83 is attached to the front end of the presser foot 9 and includes a vertical guide portion which projects downwardly into the presser foot opening 10 and at the left side of the front feed section 40.

A spring plate 84 is mounted on the presser foot 9 at the forward end thereof and at the right hand side of the opening 10, and includes a laterally extending arm 85 which overhangs the disc 20. This arm 85 is disposed in front of the path 10 of the needle 15 and under the bridge 42 of the feed dog, and the free end of said arm is formed with a forwardly extending recess 86 and a rearwardly extending finger 87. The slot 86 receives the edge a of the hem A, the arm 85 is pressed downwardly against the hem which is over the disc 20, and the finger 87 supports the edge a of the hem against the penetrating thrust of the needle 15.

The needle thread C is led forwardly through a tension 88 mounted on a bracket 89 attached to the rear end of the frame arm 8, thence through a thread guide 90 carried by a tension or control spring 91 mounted on an upstanding bracket 92 attached to the front end of the frame arm 8, and thence through a thread guide 93 formed in the top of the bracket 92. A forwardly extending bracket arm 94 is attached by a screw 95 to the forward end of the frame arm 8, and carries a stationary thread guide 96 located above the path 30 of needle travel and in alignment with the needle shaft 12. The needle thread passes from the guide 90, thence through the guide 93, thence through the guide 96, thence through a thread guide 97 attached to the lower end of the needle arm 14, 35 and then to the needle eye.

Thus it will be seen that the location of the stationary needle thread guide 96 coupled with the control spring 91 and the associated thread guide 93, the needle thread will be held taut and 40 will remain in the long groove of the needle which is formed in the underside thereof as usual. Consequently the thread will not become abraded which would occur if the thread were caused to move intermittently in and out of said groove. 45

The looper thread D is led forwardly through a tension 98 mounted on the bracket 89, thence through a guide 99 mounted on the forward end of the bracket arm 94 and located in advance of the path of needle travel, thence downwardly and 50 rearwardly to a guide 100 located on the forward end of the looper shaft 67 and adjacent the rear end of the looper 66, and thence to the looper eye 101.

Thus it will be noted that because of the position of the thread guide 99, the looper thread will be inclined between said guide 99 and the thread guide 100 at the rear end of the looper; that as the looper moves forwardly the looper thread feeds through the guide 100; that the 60 length of the looper thread between these guides 99 and 100 becomes reduced in proportion to the amount of the forward travel of the looper; that the difference in the length of the thread between the guide 99 and 100 when the looper is at the 65 forward end of its travel and when the looper is at the rear end of its stroke equals the amount of thread employed in forming the shortest stitch; that when the length of the stitch is increased, a corresponding amount of thread is pulled from 70 the supply during the last part of the forward movement of the looper; and that by reason of the location of the guide 99 the thread will remain in the groove of the looper during the backward movement thereof. 75

It is of course to be understood that the details of structure and arrangement of parts may be variously changed and modified without departing from the spirit and scope of my invention.

5. I claim:

1. In a sewing machine stitch forming mechanism, the combination with a feeding mechanism, of a threaded needle mounted for reciprocations across the line of feed, and a threaded looper mounted for reciprocations in a single straight line in the line of feed for cooperation with the needle, the looper passing above the needle in both strokes of each reciprocation.
- 10 2. In a sewing machine stitch forming mechanism, the combination with a feeding mechanism, of a threaded needle mounted for reciprocations across the line of feed and provided with a spreader groove, and a threaded looper mounted for reciprocations in a single straight line in the line of feed for cooperation with the needle, the needle-loop penetrating movement of the looper being in a direction opposite the direction of feed and the looper passing above the needle in both 15 strokes of each reciprocation.
- 15 3. In a sewing machine stitch forming mechanism, the combination with a feeding mechanism, of a threaded needle mounted for reciprocations across the line of feed, a threaded looper mounted for straight line reciprocations in the line of feed for cooperation with the needle, and means for reciprocating said looper including devices for imparting a relatively slow movement to the looper during the first part of the return travel 20 thereof.
- 20 4. In a sewing machine stitch forming mechanism, the combination with a feeding mechanism, of a threaded needle mounted for reciprocations across the line of feed, a threaded looper mounted for straight line reciprocations in the line of feed for cooperation with the needle, the needle-loop penetrating movement of the looper being in a direction opposite the direction of feed, and means for reciprocating said looper including devices for imparting a relatively slow movement to the looper during the first part of the return travel 25 thereof.
- 25 5. In a sewing machine stitch forming mechanism, the combination with a feeding mechanism, of a threaded needle mounted for reciprocations across the line of feed, a threaded looper mounted for straight line reciprocations in the line of feed for cooperation with the needle, and means for reciprocating said looper including devices for imparting a relatively fast movement to the looper during the first part of the forward travel thereof.
- 30 6. In a sewing machine stitch forming mechanism, the combination with a feeding mechanism, of a threaded needle mounted for reciprocations across the line of feed, a threaded looper mounted for straight line reciprocations in the line of feed for cooperation with the needle, and means for reciprocating said looper including devices for imparting a relatively fast movement to the looper during the first part of the forward travel thereof.
- 35 7. In a sewing machine stitch forming mechanism, the combination with a feeding mechanism, of a threaded needle mounted for reciprocations across the line of feed, a threaded looper mounted for straight line reciprocations in the line of feed for cooperation with the needle, and means for reciprocating said looper including devices for imparting a relatively fast movement to the looper during the first part of the forward travel thereof.
- 40 8. In a sewing machine stitch forming mechanism, the combination with a feeding mechanism, of a threaded needle mounted for reciprocations across the line of feed, and a threaded looper mounted for reciprocations in the line of feed for cooperation with the needle and having its needle-loop penetrating movement in a direction opposite the direction of feed, said needle being provided with a transverse seat for receiving the looper thread loop during the return stroke of the needle to thereby move said loop laterally out of the path of the forwardly moving looper.
- 45 9. In a sewing machine stitch forming mechanism, the combination with a feeding mechanism, of a threaded needle mounted for reciprocations across the line of feed, and a threaded looper mounted for straight line reciprocations in the line of feed for cooperation with the needle and having its needle-loop penetrating movement in a direction opposite the direction of feed, said needle being provided with a transverse seat for receiving the looper thread loop during the return stroke of the needle to thereby move said loop laterally out of the path of the forwardly moving looper.
- 50 10. In a sewing machine stitch forming mechanism, the combination with a feeding mechanism, of a threaded needle mounted for reciprocations across the line of feed, and a threaded looper mounted for reciprocations in the line of feed for cooperation with the needle and having its needle-loop penetrating movement in a direction opposite the direction of feed, said needle being provided with a transverse seat for receiving the looper thread loop during the return stroke of the needle to thereby move said loop laterally out of the path of the forwardly moving looper, and means for reciprocating said looper including devices for imparting a relatively fast movement to the looper during the first part of the forward travel thereof.
- 55 11. In a sewing machine stitch forming mechanism, the combination with a feeding mechanism, of a threaded needle mounted for reciprocations across the line of feed, a ridge forming element for presenting a ridge of material to the needle, a threaded looper cooperating with the needle and mounted for horizontal straight line reciprocations in the line of feed and on that side of the ridge forming element opposite the point of needle penetration, the needle-loop penetrating movement of the looper being in a direction opposite the direction of feed, said needle being provided with a transverse seat for receiving the looper thread loop during the return stroke of the needle to thereby move said loop laterally out of the path of the forwardly moving looper.
- 60 12. In a sewing machine, the combination with a frame including a forwardly extending arm, of a horizontal presser foot fixed to the front end of said arm and having an opening, a main shaft journaled in the rear end of said arm, a needle shaft extending longitudinally of and journaled in said arm, a needle mounted on said needle shaft for reciprocations above the foot and across the opening therein, driving connec- 65
- 65 70 75

tions between the main shaft and the needle shaft, a looper bar mounted on the frame arm between the main shaft and the needle for horizontal straight line movements longitudinally of the arm, means for retaining the looper bar against axial rotation, a threaded looper fixed to the forward end of the bar for cooperation with the needle, and driving connections between the main shaft and the looper bar.

13. In a sewing machine, the combination with a frame including a forwardly extending arm, of a horizontal presser foot fixed to the front end of said arm and having an opening, a main shaft journaled in the rear end of said arm, a needle shaft extending longitudinally of and journaled in said arm, a needle mounted on said needle shaft for reciprocations above the foot and across the opening theréin, driving connections between the main shaft and the needle shaft, a looper bar mounted on the frame arm between the main shaft and the needle for horizontal straight line movements longitudinally of the arm and in substantially the same horizontal plane as the main shaft, means for retaining the looper bar against axial rotation, a threaded looper fixed to the forward end of the bar for cooperation with the needle, and driving connections between the main shaft and the looper bar comprising a downwardly extending arm fixed to the looper bar, a driving eccentric fixed to the main shaft, and a pitman connected at one end to the eccentric and at its other end to the downwardly extending arm at a point below the looper bar.

14. In a sewing machine, the combination with a frame including a forwardly extending arm, of a horizontal presser foot fixed to the front end of said arm and having an opening, a main shaft journaled in the rear end of said arm, a needle shaft extending longitudinally of and journaled in said arm, a needle mounted on said needle shaft for reciprocations above the foot and across the opening theréin, driving connections between the main shaft and the needle shaft, a looper bar mounted on the frame arm between the main shaft and the needle for horizontal straight line movements longitudinally of the arm, means for retaining the looper bar against axial rotation, a threaded looper fixed to the forward end of the bar for cooperation with the needle, driving connections between the main shaft and the looper bar, and a motion top feed mechanism for feeding the fabric up to and past the needle comprising a feed dog having spaced sections respectively disposed in front of and in rear of the needle path of travel and at one side of the looper travel, a feed bar extending longitudinally of the work arm, connections between the main shaft and the feed bar for imparting up and down movements to the feed bar, and other connections between the main shaft and the feed bar for imparting back and forth movements to said feed bar.

15. In a looper thread control for sewing machines, the combination with a stitching head, of a stationary presser foot mounted on said head and provided with a longitudinal opening, a threaded needle mounted on said head for reciprocations above the foot and across the opening thereof, a threaded looper mounted on said head for cooperation with said needle and having its needle-loop entering and shedding movements across the path of needle movement, a tension for the looper thread mounted on the

stitching head, and a looper thread guide mounted on said head between the tension and the looper and located in front of the needle and in substantial alinement with the looper.

16. In a blind stitch sewing machine, the combination with a stationary presser foot having an opening, of a feeding mechanism, means for projecting a ridge of material upwardly through the opening into needle penetrating position, and a stitch forming mechanism operating entirely above the foot including a threaded needle having reciprocatory movements across said opening and in a plane transverse to the line of feed, and a cooperating threaded looper having reciprocatory movements in a single straight line in the line of feed.

17. In a blind stitch sewing machine, the combination with a stationary presser foot having an opening, of a feeding mechanism, means for projecting a ridge of material upwardly through the opening into needle penetrating position, and a stitch forming mechanism operating entirely above the foot including a threaded needle having reciprocatory movements across said opening and in a plane transverse to the line of feed, and a cooperating threaded looper having reciprocatory movements in a single straight line in the line of feed, the needle penetrating movement of the looper being in a direction opposite the direction of feed.

18. In a blind stitch sewing machine, the combination with a stationary presser foot having an opening, of a feeding mechanism, means for projecting a ridge of material upwardly through the opening into needle penetrating position, and a stitch forming mechanism operating entirely above the foot including a threaded needle having reciprocatory movements across said opening and in a plane transverse to the line of feed, a cooperating threaded looper having reciprocatory movements in a single straight line in the line of feed, and means for reciprocating said looper including devices for imparting a relatively slow movement to the looper during the first part of the return travel thereof.

19. In a blind stitch sewing machine, the combination with a stationary presser foot having an opening, of a feeding mechanism, means for projecting a ridge of material upwardly through the opening into needle penetrating position, and a stitch forming mechanism operating entirely above the foot including a threaded needle having reciprocatory movements across said opening and in a plane transverse to the line of feed, a cooperating threaded looper having reciprocatory movements in a single straight line in the line of feed, the needle penetrating movement of the looper being in a direction opposite the direction of feed, and means for reciprocating said looper including devices for imparting a relatively slow movement to the looper during the first part of the return travel thereof.

20. In a blind stitch sewing machine, the combination with a stationary presser foot having an opening, of a feeding mechanism, means for projecting a ridge of material upwardly through the opening into needle penetrating position, and a stitch forming mechanism operating entirely above the foot including a threaded needle having reciprocatory movements across said opening and in a plane transverse to the line of feed, and a cooperating threaded looper having reciprocatory movements in a single straight line in the line of feed, said needle being provided with a transverse seat for receiving the looper thread.

loop during the return stroke of the needle to thereby move said loop laterally out of the path of the forwardly moving looper.

21. In a blind stitch sewing machine, the combination with a stationary presser foot having an opening, of a feeding mechanism, means for projecting a ridge of material upwardly through the opening into needle penetrating position, and a stitch forming mechanism operating entirely above the foot including a threaded needle having reciprocatory movements across said opening and in a plane transverse to the line of feed, and a cooperating threaded looper having reciprocatory movements in a single straight line in the line of feed, the needle penetrating movement of the looper being in a direction opposite the direction of feed, said needle being provided with a transverse seat for receiving the looper thread loop during the return stroke of the needle to thereby move said loop laterally out of the path of the forwardly moving looper.

22. In a blind stitch sewing machine, the combination with a stationary presser foot having an opening, of a feeding mechanism, means for projecting a ridge of material upwardly through the opening into needle penetrating position, and a stitch forming mechanism operating entirely above the foot including a threaded needle having reciprocatory movements across said opening and in a plane transverse to the line of feed, a cooperating threaded looper having reciprocatory movements in a single straight line in the line of feed, and means for reciprocating said looper including devices for imparting a relatively slow movement to the looper during the first part of the return travel thereof, said needle being provided with a transverse seat for receiving the looper thread loop during the return stroke of the needle to thereby move said loop laterally out of the path of the forwardly moving looper.
